UNITED STATES PATENT OFFICE.

JOHN H. WARNER, OF WESTPLAINS, MISSOURI.

REGISTER.

SPECIFICATION forming part of Letters Patent No. 716,795, dated December 23, 1902.

Application filed May 14, 1902. Serial No. 107,234. (No model.)

To all whom it may concern:

Be it known that I, JOHN H. WARNER, a citizen of the United States, and a resident of Westplains, in the county of Howell and State 5 of Missouri, have made certain new and useful Improvements in Registers, of which the following is a specification.

My invention is an improvement in registers, and has for an object to provide a register in connection with a cigar-cutter whereby to register the number of cigars cut; and the invention consists in certain novel constructions and combinations of parts, as will be hereinafter described and claimed.

15 In the drawings, Figure 1 is a perspective view of the cigar-cutter provided with my register, and Fig. 2 is a top plan view thereof. Fig. 3 is a cross-section illustrating the manner in which the back plate fits the top 20 of the base-plate of the cigar-cutter. Fig. 4 is a top plan view of the register, the hands and dial-plate being removed; and Fig. 5 is a detail perspective view illustrating the sliding operating-bar and the cross-lever connected 25 therewith and the supports and actuating devices for such parts.

The cigar-cutter A has a fixed blade B and the pivoted rocking blade C, pivoted at C' and provided with a projecting pin C², which 30 serves the double purpose of limiting the movement of the blade C and also operating the register.

The register D has a case E fitting over the operating parts and secured to form a case 35 for the operating parts and the dial of the register. This case E has at one side an opening E', through which projects the cross-lever which connects with the operating-slide, as presently described. The frame-plate F 40 of the register is secured upon the back plate G, which has a shoulder G' abutting the edge of the base-plate of the cigar-cutter and is secured to the cigar-cutter by means of screws G². The frame-plate F has bearings for the 45 main arbor H, which carries the master-wheel I, toothed for engagement by the pallet and detent, presently described. A frame-bar J is secured at its outer end to the frame-plate F and has at its inner end a bearing for the 50 arbor H. This frame-bar J is spaced away from the frame-plate between its ends, permitting the passage beneath it of the cross-

lever K, presently described. The arbor H carries the units-hand L, and the multiplying-hand L' is carried on an arbor M, having 55 a toothed wheel M' arranged to be operated by a spur or projection in connection with the master-wheel I, so the master-wheel will advance the multiplying-wheel one step at each revolution of the master-wheel. A detent N prevents any retrograde movement of the master-wheel, and said wheel is advanced step by step by means of the cross-lever K, pallet O, the operating-slide R, and the co-operating parts, presently described. The 60 cross-lever K is pivoted at K', extends thence beneath the frame-bar J, is provided between its ends with the pallet O, pivoted at one end O' to the cross-lever and arranged at its point to engage the teeth of the master-wheel, a keeper O² overlying the point of the pallet and retaining same in position to engage the master-wheel, and the outer edge of the pallet O being recessed at O³ to receive the point of the spring O⁴, which spring is 65 held at one end and has its free end deflected to bear within the recess O³ of the pallet and tends to force said pallet into engagement with the master-wheel, the pallet sliding along the free end of the spring O⁴ and being actuated by said spring into contact with the master-wheel, as shown. The cross-lever is provided at a point between the pallet O and its outer end with an upwardly-projecting portion or post P, perforated at P' to receive the 70 free end of the spring-rod Q, which is held at one end to the frame-plate F and fits at its free end in the perforation P' in such manner as to readjust the cross-lever and the parts connected therewith to normal position, the 75 rod sliding through the perforation P', as shown. The outer end of the cross-lever projects through an opening E' in the case and is perforated at k to receive the pin or stud R' on the operating-slide R. This operating-slide has the arm R², carrying the stud R', 80 perforated at r to receive the guide-rod S, which is fixed at one end S' and free at its outer end, so it can conform to the path of the operating-slide, a pin T on the back plate 85 standing adjacent to the free end of the spring S and forming a guide for the operating-slide, the free end of said slide being guided between pins T' T² and beneath an overlying 90 95 100

plate T³. This operating-slide is provided with an upright arm U, which is in the path of pin C² on the rocking blade of the cigar-cutter, so the said pin as it swings in its arc 5 will strike the upright arm U and move the operating-slide longitudinally sufficiently to advance the master-wheel one step.

By the described construction it will be noticed the cigar-maker as he cuts the end of 10 each cigar operates the register, so that he can at a glance determine the number of cigars made, whether the same are made by hand, in bunching means, or otherwise, the register keeping account of the number of 15 cigars cut.

Having thus described my invention, what I claim as new, and desire to secure by Letters Patent, is—

1. In a register substantially as described 20 the combination of the frame-plate, the master-wheel, the frame-bar, the main arbor secured to the master-wheel and having bearings in the frame-plate and the frame-bar, the multiplying-wheel arranged for operation 25 by the master-wheel, the detent for the master-wheel, the cross-lever extending beneath the frame-bar, pivoted at its inner end and projecting at its outer end in position for connection with the operating-slide, the pallet 30 pivoted at one end to the cross-lever, arranged at its other end to engage the master-wheel and provided in its outer side with a recess, the actuating-spring arranged at one end to operate in said recess and press the pallet into 35 engagement with the master-wheel, the post or projection on the cross-lever between the pallet and the outer end of said lever and having a perforation for the spring-rod, the spring-rod held at one end and operating at 40 its other end in the said perforation, and the operating-slide secured to the cross-lever and having an upright arm adapted for engagement and operation by a projecting pin on a 45 rocking cigar-cutter blade, substantially as set forth.

2. The combination in a register substantially as described of the cross-lever having a pallet for operating the master-wheel, the master-wheel engaged by said pallet, the cross-lever 50 being provided near its outer end with the perforation for the stud on the operating-slide, the operating-slide having a post perforated for the guide-rod and supporting a stud operating in the perforation of the cross-lever, the guide-rod fitting in the perforation 55 in the post of the operating-slide whereby the slide is guided at one end, and guide devices

for the other end of the operating-slide, said slide being provided with an arm for engagement by the swinging operating device substantially as set forth.

3. The combination with the master-wheel, the frame-plate, the main arbor and the frame-bar secured to the frame-plate and having a bearing for the main arbor and spaced between its ends away from the frame-plate, the cross-lever extending between the frame-bar and the frame-plate and pivoted at its inner end and provided between its ends with the pallet, the spring for actuating said pallet 65 into engagement with the master-wheel, the spring for retracting the cross-lever, and the operating-slide connected with the cross-lever whereby to operate the same, substantially as set forth.

4. The improvement in registers herein described, comprising the master-wheel, the main arbor secured to the master-wheel, the frame-plate and frame-bar provided with bearings for the main arbor, a multiplying-wheel arranged for operation by the master-wheel, the detent for the master-wheel, the pivoted cross-lever, extending beneath the frame-bar and projecting at its other end in position for connection with the operating-slide, the pallet pivoted at one end to the cross-lever, arranged at its other end to engage the master-wheel and provided with a recess in its outer side, the actuating-spring operating at one end in said recess and arranged to press the pallet into engagement with the master-wheel, the post on the cross-lever between the pallet and the outer end of the lever and provided with a perforation, the spring-rod operating at one end in said 95 perforation and suitably held at its other end, and the operating-slide secured to the cross-lever and provided with means whereby it may be operated, substantially as set forth.

5. A cigar-cutter having a rocking cutting-blade provided with a pin or projection, and a register supported in connection with the cutter and having an operating-slide provided with an upright arm for engagement by the pin or projection on the rocking cutting-blade whereby as the cutter is swung in operation its pin or projection will operate upon the upright arm of the operating-slide to effect the operation of the register substantially as set forth.
